UNITED STATES PATENT OFFICE

LUISE BIERBICHLER, NÉE SCHMIDT, OF INCHENHOFEN, NEAR AICHACH, GERMANY

BABY'S SUCKING BOTTLE

Application filed November 30, 1927, Serial No. 236,859, and in Germany March 23, 1927.

This invention relates to an improvement in a baby's sucking bottle, and more particularly to an improved two-part envelope for the latter having the property of keeping the bottle warm and at the same time preventing an unintended removal of the rubber tit therefrom.

The novelty consists in the fact that the envelope is made of two halves hinged at their lower ends and tightly overlapping one another at their butt-edges, while a screwed ring which at the same time secures the rubber tit on the bottle holds the upper ends of the two envelope halves securely together by engaging over the screw-threaded neck of the envelope.

The accompanying drawing illustrates in Figs. 1 and 2 the improved envelope attached to a baby's sucking bottle, in a vertical section and in a cross-section respectively.

The baby's sucking bottle *a* is enclosed by an envelope *b* having an inner lining *c* of heat-impermeable material and consisting of two halves hinged at their lower ends at *e* beneath the bottom of the bottle and tightly overlapping one another at their butt-edges *d*, while an annular recess *f* is provided directly below the screw-threaded neck *g* of the envelope for the reception of the bead *h* at the inner end of the rubber tit *i* of the sucking bottle and a screwed ring *k* is placed over said tit and screwed on the neck of the envelope thereby keeping the two halves of the latter securely in position and preventing an unintended removal of the rubber tit from the bottle.

What I claim is:—

A two-part envelope for baby's sucking bottles, in combination with a screw-threaded neck and a screw-threaded ring, comprising two halves tightly overlapping one another at their butt-edges, an inner heat-impermeable lining on said envelope, and an annular recess in the envelope arranged directly be-

low the screw-threaded neck and intended for keeping the rubber tit edge in position during the use of the bottle.

In testimony whereof I have hereunto set my hand.

LUISE BIERBICHLER, née SCHMIDT.
